RING BINDER OR THE LIKE

William J. Sibley, South Hadley, Mass., assignor to
National Blank Book Company, Holyoke, Mass., a
corporation of Massachusetts

Filed Feb. 3, 1961, Ser. No. 63,815

Term of patent 14 years

(Cl. D6—1)

Fig. 1.

Fig. 2.

FIG. 3.

FIG. 4.

FIG. 5.

FIG. 6.

FIG. 1 is a plan view of a ring binder embodying my new design;

FIG. 2 is a plan view of the inside thereof as it appears in open position;

FIG. 3 is a plan view of the outside thereof;

FIG. 4 is a bottom edge view of the binder as seen in FIG. 2; and

FIGS. 5 and 6 are fragmentary sectional views on lines 5-5 and 6-6, respectively, of FIG. 3.

The essential features of my design reside in those portions indicated by solid lines.

I claim:

The ornamental design for a ring binder or the like, as shown and described.
